UNITED STATES PATENT OFFICE.

ICHIRO NOZAWA, OF TOKYO, JAPAN.

STEEL OR IRON PILLAR PARTICULARLY ADAPTED FOR MOUNTING ELECTRIC WIRES.

Application filed May 11, 1923. Serial No. 638,371.

The invention relates to steel or iron pillars of a hexagonal shape in cross section at the point of horizontal bracing, particularly adapted for mounting electric wires. 5 Heretofore a pair or pairs of 90 degree angle iron or steel have been used with diagonal bracings on each outer side but there is a drawback that resistance to bending and twisting is not so great as could be expected. Besides the manipulation in 10 using 90 degree angle iron or steel is sometimes difficult due to the particular angularity, and in case where such iron or steel longitudinally bent at right angle, available 15 in the market, is employed to form a column, it is liable to fracture at the angular point. It has been heretofore unsuccessful to use other angle irons or steels than the ones of 90 degree but according to my 20 invention, angle irons or steels of 120 degree angularity or from about 110 degree to 140 degree, drawn or bent, are utilized to form a pillar to a greater advantage than in the case of 90 degree angle iron or steel. 25 The foregoing and other features are hereinafter referred to and the preferred embodiment of the invention will now be described with reference to the accompanying drawings in which, 30 Fig. 1 is a cross section of the pillar; Fig. 2, a fragmental elevation; Fig. 3, a front elevation of whole pillar completely equipped; Figs. 4 and 5 are diagrammatic views of cross sections of arrangements of 35 columns illustrated to explain the comparative advantages of the present construction over other constructions.

As shown in Figures 1 and 2, the sides A and A' of one column are made equal to 40 each other and the sides B and B' of another column are likewise equal to each other, with the angle subtended by the sides A and A' and the angle by the sides B and B' being each equal to the interior angle of a 45 regular hexagon, these four sides constituting four sides of a hexagon.

In this way the material to form each column is drawn or longitudinally bent, as the case may be and AA' and BB' represent 50 columns both of which constitute a pillar body as claimed in this application. Both columns are jointed with horizontal bracing *c*, connected to the members A' and B' by welding, riveting, or other usual 55 means, and arranged in spaced relation to form a rigid pillar which is a hexagonal

pillar as shown in Figure 1 in cross section.

Before proceeding to specifically describe the invention, let us suppose the weight of electric wires mounted on the pillar is the 60 only load on the latter. The pillar may be assumed as a long column or beam, one end of which is fixed and other end free, on which free end a force *P* equal to the load resulting from the weight of carried electric 65 wires is acting.

According to Euler's formula,

$$P = \frac{4\pi^2 EI}{L^2}$$

70

where *P*=collapsing load.

E=Young's modulus.

I=Moment of inertia of a cross section.

L=Length of the pillar.

75

It will be seen that where *E* and *L* are constant, as in the case of pillars or the like of equal lengths and same quality of material, the collapsing load varies in direct proportion to the value of moment of inertia.

Further suppose that by some accident wires on one side of the pillar are broken or that wind pressure on the wires is assumed as the only load to be taken into consideration, the pillar may be regarded as a beam, one end of which is supported and other end free on which beam an isolated load or uniformly distributed load is acting. 85

In this case,

$$M = \frac{EI}{\rho}$$

95

where *M*=Resisting moment.

\rho=Radius of curvature of neutral axis of the beam.

It follows therefore that if *E* and *\rho* are constant, in other words, if pillars are constructed of same material, resisting moment varies in direct proportion to moment of inertia of the cross section. The above constitutes the basis of the theoretical treatment given below in order to exemplify the 100 novelty and utility of the present invention.

In Figure 4 there is shown an arrangement in which the column is formed of members having equal sides *a* and *a'* drawn or bent at a right angle. In this figure XX' 105 represents a horizontal neutral axis and YY' a vertical neutral axis.

According to the present invention, the material may be longitudinally bent or drawn to form 120 degree angles equal to the inner angle of a hexagon or about 110 degree to 140 degree instead of 90 degree in the preceding figure. This is diagrammatically shown in Figure 5.

Let r represent the distance from neutral axes XX' and YY' to the cross sectional area da of each particle of the material, then the moment of inertia of the whole cross section is theoretically,

$$I = \int r^2 da$$

Now suppose as shown in Figures 4 and 5, the sides aa' should be made equal to each other and of the same cross sectional areas. The total sum of the areas of the particles is the same in Figures 4 and 5 but as the value of r in Figure 4 is considerably smaller than r in Figure 5, the total sum of $r^2 da$, that is,

$$\int r^2 da$$

is considerably less in Figure 4. This means that the moment of inertia in Figure 5 is far greater than in Figure 4.

It is also noted that while the construction in Figure 4 is difficult in manufacture due to the particular angularity of the sides, that of Figure 5 is more adapted to manipulation on account of that the sides are outwardly flared.

I wish now to point out various advantages gained by my invention.

(1) The present pillar which is mostly

intended for mounting electric wires gives more resistance to bending and twisting strains.

(2) As the angles between the sides of the columns are each about 120 degree, there is a decided advantage in readily mounting necessary arms and brackets for electric wires.

(3) As the angles between the sides of the columns are each obtuse angle, there is no tendency of the material being fractured in bending treatment.

(4) The pillar constructed in accordance with this invention gives a beautiful appearance due to harmony of the constituent parts.

(5) Although a single column having an obtuse angularity between two longitudinal parts is not so strong as one of 90 degree, the assemblage of a pair of same to form a spaced pair of two contiguous sides of a hexagon in cross section affords greater strength than the similar arrangement of columns of 90 degree angularity.

What I claim is:

A column for supporting electric wires, comprising, two upright steel angle members, each member having two plane sides meeting at an angle of approximately 120°, the steel members being placed facing each other with their apexes outward, and spaced so as to form in cross section, four sides of a regular hexagon, and braces rigidly connecting the members together.

Signed at American Embassy, Tokyo, this 17th day of April A. D., 1923.

ICHIRO NOZAWA.
